UNITED STATES PATENT OFFICE.

FRANK FULTON REDDING, OF NEW YORK, N. Y.

STARTING-CRANK FOR MOTORS.

1,374,114.

Specification of Letters Patent.

Patented Apr. 5, 1921.

Application filed September 19, 1919. Serial No. 324,753.

To all whom it may concern:

Be it known that I, FRANK F. REDDING, a citizen of the United States, and a resident of the city of New York, borough of Queens, in the county of Queens and State of New York, have invented a new and Improved Starting-Crank for Motors, of which the following is a full, clear, and exact description.

This invention relates to new and useful improvements in internal combustion engines, and it pertains more particularly to a starting mechanism therefor.

The primary object of the invention is to provide a starting mechanism for internal combustion engines commonly employed in motor vehicles, and more particularly to engines used in trucks.

In motors employed for furnishing power for trucks, self-starting devices are not commonly employed, it being the general practice to start said motors by hand-cranking operation. Furthermore, in engines of this character the compression is greater than in the smaller high speed, and, therefore, greater effort is necessary to perform the cranking operation.

It is a further object of the invention to provide means for preventing a movement of the starting crank in the reverse direction, which action sometimes occurs owing to a premature expansion in the motor cylinders and resulting in injury to the operator.

With the above and other objects in view, reference is to be had to the accompanying drawings, in which—

Figure 1 is a horizontal sectional view of the improved mechanism with a portion of the motor vehicle and motor shown in plan;

Fig. 2 is a sectional view taken on the line 2—2 of Fig. 1;

Fig. 3 is a sectional view taken on the line 3—3 of Fig. 1;

Fig. 4 is a detail elevation of one of the connecting and disconnecting means, and

Fig. 5 is a sectional view taken on the line 5—5 of Fig. 1.

Referring more particularly to the drawings, the reference character 6 designates a portion of the motor vehicle frame, the forward end of the crank shaft of the motor being designated by the reference character 7. The forward end of the crank shaft 7 is provided with ratchet teeth 8, and rotatably mounted in the motor frame 6, is a shaft 9,

the rear end of which is provided with ratchet teeth 10, adapted to engage with the ratchet teeth 8 of the forward end of the crank shaft 7 for the purpose of rotating the latter to start the motor. The reference character 11 designates a housing, and said housing is provided with an annular flange 12, which is perforated as indicated by the reference character 13, for the reception of suitable securing means 15, which in the present instance, is shown as bolts. The housing 11 is provided with a rear plate 16 and a front plate 17. The rear plate 16 is suitably secured to the motor vehicle frame 70 in any desired manner. The front plate 17 is also suitably secured to the open end of the housing 11 to form a closing plate therefor, and said closing plate is provided with a central opening 18, the purpose of 75 which will be hereinafter more specifically described.

The rear plate 16 is provided at equidistantly spaced intervals with a plurality of pins 19, and pivotally mounted on each of said pins 19, is a pawl 20. Rigidly secured as at 21, to each of said pawls, is a spring 22, the free end of which projects beyond the pawl and engages behind a pin 23, as shown in Fig. 2. The plate 16 is further 80 provided with a hub extension 24, and rotatably mounted on said hub extension 24, is a ring 25, said ring being provided on its periphery with a plurality of teeth 25 with which the pawls 20 are adapted to engage 90 for a purpose to be hereinafter more specifically described. The front face of this ring 25 is provided with a plurality of teeth 27, and adapted for engagement with the teeth 27, are a plurality of teeth 28, carried 95 on the rear face of a member 29, which is splined to the forward end of the shaft 30 by means of a key 29.

The reference character 31 designates an internal annular flange integral with the 100 casing 11, and said annular flange serves the double function of retaining the ring 25 in position, as well as forming the means by which the gears 32 are rotatably mounted within the casing, it being understood that 105 said gears carry pinions 33 and 34, which engage in the annular flange 31 and the front plate 17, respectively. The member 29 here- 110 fore mentioned is provided with a plurality of peripherally arranged teeth 35, which are adapted to engage with the teeth of the gears 32, as best shown in Figs. 1 and 3,

Rotatably mounted on the forward extension 30 of the shaft 9, is a member 40, which has a reduced tubular extension 41, and said member 40 is provided with a plurality of 5 teeth 42, which engage with the teeth of a large gear wheel 43 carried by and operated with the small gears 32 heretofore mentioned.

The reference character 44 designates a 10 starting crank, and said crank is adapted to be positioned on the reduced tubular extension 41 and secured thereto by means of a wing nut 45 and bolt 46, when it is desired to crank the engine through the gearing 15 heretofore described for giving increased power to the cranking operation.

Keyed to the free extremity of the forward extension 30 of the shaft 9, as by means of the transverse key 46, is a sleeve 47, and 20 said sleeve 47 is spaced from the forward end of the reduced tubular extension 41 by a washer or the like 48.

When it is desired to crank the motor directly without employing the gears, said 25 starting crank 44 is secured to the sleeve 30.

The operation of the device is as follows: With the crank handle 44 attached to the reduced tubular extension 41, if it be pushed inwardly or to the left in Fig. 1, it will be 30 seen that the teeth of the members 8 and 10 will be engaged with each other, and that the crank shaft 7 will be operatively connected with the shaft 9. This movement likewise engages the teeth 27 and 28 of the 35 members 25' and 29, respectively, so that said members are operatively connected in such a manner that they will rotate in unison.

If now a rotary motion be imparted to the crank handle 44, it will be seen that through 40 the medium of the gear teeth 42 meshing with the gears 43, said gears will be rotated and through the medium of the gear wheels 32 meshing with the teeth 35 of the member 29, said member 29 will likewise be rotated, 45 and through the medium of its teeth 28 in engagement with the teeth 27 of the ring 25', said ring 25' will likewise be rotated. The rotation of this ring is permitted by reason of the teeth 25 riding under the several pivoted pawls 20.

By this arrangement through the medium of this reducing gearing upon every two revolutions of the crank handle 44, one revolution of the crank shaft 7 will be obtained, 55 thus reducing the power required for rotating the crank shaft 7.

With the parts in the position described in the foregoing, should a premature explosion take place in any of the cylinders of the motor and the shaft 7 be rotated in the reverse 60 direction, it will be seen that the tendency to reverse the member 25' in the opposite direc-

tion will be overcome by reason of the engagement of the pawls 20 with the teeth 25. If the ring 25' is prevented from reversing, 65 it will be seen that as the shaft continues to rotate, the teeth 27 and 28 will be disconnected by reason of the teeth 28 riding backwardly on the teeth 27, and that in disconnecting said teeth, the member 29 will be 70 moved longitudinally of the shaft extension 30, and at the same time, this movement is employed to disconnect the members 8 and 10 in such a manner as to prevent a driving in the reverse direction of the shaft 30 and 75 the crank handle 34.

From the foregoing, it will be apparent that the present invention provides means whereby less power is required for starting motors in which the cylinder compression is 80 high, and, at the same time, a device is constructed in which any back kick of the motor owing to a premature explosion or any other cause, is obviated.

Having thus described the invention, what 85 is claimed as new is:

1. A starting device comprising a shaft adapted to be directly connected to the crank shaft of the motor to be started, a sleeve loosely mounted on said shaft, a plurality of 90 members carried by said shaft and adapted for driving interengagement with each other, one of said members being keyed to the shaft and the other free to rotate thereabout, means operated by the sleeve for driving the 95 member keyed to the shaft when said sleeve is rotated in one direction, and means for preventing movement of the other of said members upon movement of the sleeve in the opposite direction. 100

2. A starting device for motors comprising a shaft adapted to be directly connected to the crank shaft of a motor to be started, a gear keyed to said shaft, means for driving said gear and shaft from said sleeve in one direction, and means for preventing movement of said gear and sleeve in the opposite direction, said means serving to automatically disconnect the shaft and motor crank shaft. 110

3. A starting device for motors comprising a shaft adapted to be directly connected to the crank shaft of the motor to be started, a sleeve loosely mounted on said shaft, a gear keyed to the shaft and having a notched face, a member mounted for free rotation about the shaft and having a notched face adapted for interengagement with the notched face of said gear, means for driving the gear keyed to the shaft from the sleeve loosely 115 mounted thereon, and means for preventing a movement of the sleeve and gear keyed to the shaft in opposite directions. 120

FRANK FULTON REDDING.
